United States Patent Office.

JAMES SUTLIFF, OF EAST BOSTON, MASSACHUSETTS.

Letters Patent No. 77,414, dated April 28, 1868.

IMPROVEMENT IN STEAM-GENERATORS.

The Schedule referred to in these Letters Patent and making part of the same.

TO ALL WHOM IT MAY CONCERN:

Be it known that I, JAMES SUTLIFF, of East Boston, in the county of Suffolk, and in the State of Massachusetts, have invented certain new and useful Improvements in Steam-Bridge Wall; and do hereby declare that the following is a full, clear, and exact description thereof, reference being had to the accompanying drawings, and the letters of reference marked thereon.

In the annexed drawings, making a part of this specification, A represents a steam-boiler, and B the steam-drum thereof, constructed in any of the usual ways, and of dimensions to suit. C represents a steam-bridge wall, made of boiler-iron, and hollow, the sides braced and held together by means of hollow bolts *g*. The bridge-wall C is made of any desired dimensions, and has the boiler A adjusted or secured to or in the sides thereof, as shown, the top of said wall being made concave, to correspond with the convexity of the boiler. A feed-pipe, *d*, connects this wall C with the boiler A, and through it water passes from said boiler to feed or into the wall C. Steam-pipes *ff* connect the top of the wall C with the drum B of the boiler, or may connect with the boiler direct when a drum is not used.

It will readily be seen that all sediment and solid matter will pass down through the feed-pipe *d* into the wall C, and may be readily and conveniently cleaned out by means of a man-hole on one end, and a pipe, *h*, provided with a cock, at the other end.

By the use of this wall it will be seen that much more steam is procured by the same fire or amount of fuel than by any other known device, and that the boiler may be kept clean much easier.

Having thus fully described my invention, what I claim as new, and desire to secure by Letters Patent, is—

The hollow steam-bridge wall C, the sides braced by the hollow bolts *g*, and connected to the boiler-pipes *f* and *d*, constructed and arranged substantially as and for the purpose set forth.

In testimony that I claim the foregoing, I have hereunto set my hand and seal, this 28th day of January, 1868.

JAMES SUTLIFF. [L. s.]
